UNITED STATES PATENT OFFICE

HENRY I. LEA, OF PITTSBURG, PENNSYLVANIA, ASSIGNOR TO THE WESTINGHOUSE MACHINE COMPANY, A CORPORATION OF PENNSYLVANIA.

GAS-PRODUCER.

No. 881,100.

Specification of Letters Patent. Patented March 3, 1908.

Application filed July 27, 1905. Serial No. 271,413.

To all whom it may concern:

Be it known that I, HENRY I. LEA, a citizen of the United States, and a resident of Pittsburgh, in the county of Allegheny and 5 State of Pennsylvania, have invented a new and useful Improvement in Gas-Producers, of which the following is a specification.

This invention relates to gas producers.

In the manufacture of producer gas the 10 greatest difficulties so far encountered have been the maintenance of proper conditions in the fuel bed and the attendant difficulty of properly controlling the blast in its passage therethrough.

15 The tendency of the blast is to pass through the gas generating chamber along the lines of least resistance and since with the ordinary methods of charging the generating chamber, the interior or central portion of 20 the fuel bed is the most compact part, the blast tends to pass through the outer portion of the fuel bed adjacent to the producer walls: again, the protecting hood with which the blast twyer is usually provided, tends to 25 cause the blast to flow towards the walls of the producer and to be shunted around the central part of the fuel bed.

In the burning of carbon the first product 30 of combustion is CO_2 and not as is generally supposed, CO . In a producer, CO_2 is formed at the point where the blast first meets the incandescent fuel and then in passing through 35 the fuel bed, is converted into CO by combining with the incandescent carbon with which it is in contact.

With the difficulties above cited the CO_2 , does not come in contact with sufficient carbon to convert it into CO and consequently the gas leaving the fuel bed has an unduly 40 high content of CO_2 . To avoid these difficulties, I propose to so introduce the fuel into the gas generating chamber that the minimum depth of fuel bed will be at the center of the generating chamber and the greatest 45 weight of fuel, and consequently the most compact portion of the fuel bed, will be adjacent to the producer walls. By this arrangement the natural path of the gas will be from the blast twyer (because of the entering 50 velocity of the blast and because of the hood with which the blast twyer is provided), towards the walls of the chamber and then—since its velocity is decreased—along the lines of least resistance back towards the center of the fuel bed. Since, with this con-

struction, the path of least resistance for the blast extends diagonally across the fuel bed from the walls of the generating chamber towards its center, all the fuel entering the chamber will pass at least once through the 60 blast current.

The object of this invention is, therefore, the production of a gas producer in which new and improved means are utilized for introducing the fuel.

65 A further object is the production of a combined producer and auxiliary steam boiler in which simplicity of construction and ease of manipulation are characteristic features.

These and other objects I attain in an apparatus embodying the features herein described and illustrated.

In the single sheet drawing accompanying 70 this application and forming a part thereof, a vertical section of a gas producer embodying this invention is shown.

A gas producer comprising a gas generating chamber 2 and a steam boiler 3 is provided with an inclosing shell 4, the lower portion of which extends into a water-basin 5 80 constituting a water seal for the chamber 2. An annular flange 6 is suitably connected to the shell portion 4 and supports a fire brick lining 7, with which the chamber 2 is provided. Suitably arranged sight holes 8 ex- 85 tending through the lining 7, are provided with suitable covers 9. Poke holes 10 are annularly arranged near the top of the chamber 2, and provided with suitable closing means 11. The fire brick lining adjacent 90 to the poke holes is cut away as shown, and consequently much freedom in stirring the fuel bed is obtained, as a wedge-shaped opening permits the insertion of a crooked poking bar and various positions may be obtained 95 which are impossible with a cylindrical opening through the lining.

A blast twyer 12, which is provided with a suitable hood 15, enters the lower portion of the chamber 2 and is connected to a passage 100 13, to which is connected a steam blower 14. A rotary grate 16 is provided with operating means 17 and is adapted to discharge the ash into the water-basin 5. The steam boiler 3 is provided with a cast iron inclosing shell 19 105 which is supported by suitable brackets 20, riveted or otherwise connected to the shell portion 4. The boiler 3 is also connected to a hood portion 21 which is attached to the shell portion 4 by the flange connection 22. 110

The hood portion 21 is provided with a central chamber 23 inclosed by walls 24 which are connected to the exterior walls 25 of the hood portion by a number of suitably arranged webs 26.

An annular or cone shaped passage 27 is inclosed between the walls 24 and 25 and connects with an annular passage 28 between the cast iron shell 19, surrounding the boiler, 10 and the exterior shell 4 of the producer. Poke holes 38, suitably arranged in the walls 25, provide access into the passage 28.

The hood portion 21 is provided with a fuel charging device 29 which connects 15 through an opening 30 with the passage 27. The chamber 23 incloses the upper ends of the boiler tubes 18 and is thereby connected with the producer chamber 2. A gas offtake port 31, with which the chamber 23 is provided, extends through the exterior wall 25 and is adapted to be connected to gas cleaning apparatus or to gas consuming appliances. The boiler 3 is provided with suitable steam pipe 32 which connects with the blower 14 20 and to which is attached a safety valve 34. The boiler is also provided with a suitably valved feed pipe 35, water-glass 36, and steam-gage 37.

The charge of coal or other fuel is introduced into the passage 27 by the charging means 29 and passing through the annular passage 28 enters the gas generating chamber 2. By this arrangement the fuel bed in the generating chamber will be a minimum depth 35 at the center, (as shown by the dotted line 39) the coal being deposited around the outer edge of the fire. The passage 28 around the boiler being filled with green coal does away with the necessity of boiler lagging as the 40 body of descending coal acts as a guard against heat radiation, and all the heat absorbed by the coal is manifestly not lost. The shell 19 prevents the relatively cold fuel from coming in contact with the shell of the 45 boiler and the boiler is thus protected from the changes in temperature due to irregular firing. The poke holes 38 are provided to aid the passage of the fuel through the passage 28.

50 Since the fuel lying next to the lining and adjacent to the poke holes 10 is not in the direct line of blast, it is relatively cold, and the thin lining utilized is therefore not objectionable. A further advantage of this arrangement is that the excessively hot portions of the fuel bed is at its interior and in case of excessive heating and the formation

of clinkers, such formation will occur in the center of the fuel bed and not at the side, where it may attach itself to the brick lining 60 and seriously interfere with the successful operation of the producer. Any clinker formed in the center of the fuel bed is gradually worked down and out of the producer without seriously affecting the operation. 65 The construction of this style of producer is particularly cheap and its erection is very simple. The method of having the coal supplied to the periphery of the fuel bed will apply with equal advantage to producers designed for handling bituminous or anthracite coal with up-drafts and with slight modifications and the elimination of the boiler may also be utilized with down-draft producers. 75

Having now described my invention what I claim as new and useful and desire to secure by Letters Patent is:

1. In a gas producer, a gas generating chamber, a superimposed steam generator, 80 gas passages extending therethrough, a hood provided with a gas offtake inclosing the ends of said gas passages and a fuel charging passage inclosing said hood and encircling said steam generator, adapted to introduce 85 fuel adjacent to the walls of said generating chamber.

2. In a gas producer, a gas generating chamber, a superimposed steam generator, 90 gas passages extending through said generator, means provided with a gas offtake port inclosing the ends of said passages for collecting the gas delivered therefrom, a fuel charging device and a passage surrounding said means and said generator for delivering 95 fuel from said device to said gas generating chamber.

3. In a gas producer, a gas generating chamber, a superimposed boiler, gas passages extending therethrough and communicating 100 with said chamber, a collecting chamber communicating with the upper ends of said gas passages and provided with a gas delivery port, a fuel feeding device located above said collecting chamber and a passage around 105 said chamber and said steam generator for delivering fuel from said device to said gas generating chamber.

In testimony whereof I have hereunto subscribed my name this 21st day of July 1905. 110

HENRY I. LEA.
